US0D1055862S

(12) **United States Design Patent** (10) **Patent No.:** **US D1,055,862 S**
(45) **Date of Patent:** **** Dec. 31, 2024**

(54) **CONNECTOR PAIR**

(71) Applicant: **Molex, LLC**, Lisle, IL (US)

(72) Inventors: **Thomas R. Marrapode**, Naperville, IL (US); **Jesus Enrique Fung**, Westmont, IL (US); **Andrew Kolak**, Villa Park, IL (US); **Wenzong Chen**, Naperville, IL (US); **Sung-Ping Huang**, Hsinchu (TW); **Chih Chung Wu**, Hsinchu (TW); **Sheng-Pin Su**, Hsinchu County (TW); **Chien-Lang Tai**, Hsinchu (TW)

(73) Assignee: **Molex, LLC**, Lisle, IL (US)

(**) Term: **15 Years**

(21) Appl. No.: **29/839,637**

(22) Filed: **May 23, 2022**

(51) LOC (14) Cl. **13-02**

Assistant Examiner — Devin Kelly

(57) **CLAIM**

The ornamental design for a connector pair as shown and described.

DESCRIPTION

FIG. 1 is a front perspective view of one piece of a connector pair showing our new design;

FIG. 2 is a front perspective view of the second piece of a connector pair showing our new design;

FIG. 3 is a perspective view of the engaging portions of the connector pair of FIGS. 1-2 shown side-by-side with the view of the second piece corresponding to a partial sectional view identified by line 3-3 of FIG. 2; and,

FIG. 4 is a front view of the engaging portions of the connector pair of FIGS. 1-3 shown side-by-side.

The broken lines depicting the remainder of the connector pair form no part of the claimed design.

1 Claim, 4 Drawing Sheets
